DESIGN FOR A GOLF CLUB CARRIER

Thomas Cross, Saginaw, Mich.

Application April 12, 1945, Serial No. 118,959

Term of patent 7 years

(Cl. D14—3)

To all whom it may concern:

Be it known that I, Thomas Cross, a citizen of the United States, residing at Saginaw, in the county of Saginaw and State of Michigan, have invented a new, original, and ornamental Design for Golf Club Carrier, of which the following is a specification, reference being had to the accompanying drawing, forming part thereof.

In the drawing,

Fig. 1 is a front view in perspective of a golf club carrier embodying my design, the view showing the handle portion as it appears in raised position.

Fig. 2 is a rear view also in perspective, the handle portion being shown as it appears in position for use.

The characteristic features of my design are shown by means of full lines in the drawing.

I claim:

The ornamental design for a golf club carrier, as shown and described.

THOMAS CROSS.
